Primary Examiner — David G Muller(74) *Attorney, Agent, or Firm* — Epstein Drangel LLP;
Robert L. Epstein(57) **CLAIM**

The ornamental design for a colostrum collector, as shown and described.

DESCRIPTION

FIG. 1 is a top, front, left side perspective view of a colostrum collector embodying my new design;

FIG. 2 is a bottom, rear, right side perspective view thereof;

FIG. 3 is an exploded perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines shown in the figures depict portions of the colostrum collector that form no part of the claimed design.
